FURNITURE PANEL OR SIMILAR ARTICLE

Richard M. Chapin, Charlotte, N.C., assignor to Dolly
Madison Industries, Huntingburg, Ind.

Filed Jan. 4, 1971, Ser. No. 103,961

Term of patent 3½ years

Int. Cl. D6—99

U.S. Cl. D6—193

FIG. 1 is a front elevational view of one embodiment of a furniture panel or similar article showing my new design;

FIG. 2 is a top plan view of the decorative furniture panel shown in FIG. 1;

FIG. 3 is a front elevational view of another embodiment of a furniture panel or similar article showing my new design;

FIG. 4 is a top plan view of the decorative furniture panel shown in FIG. 3.

The backs of each of the embodiments of the furniture panel or similar article shown are substantially plain and unornamented.

I claim:

The ornamental design for a furniture panel or similar article, substantially as shown and described.
